UNITED STATES PATENT OFFICE.

HENRY BARDSLEY, OF PROVIDENCE, RHODE ISLAND, ASSIGNOR TO CROMPTON & KNOWLES
LOOM WORKS, A CORPORATION OF MASSACHUSETTS.

LOOM PATTERN MECHANISM.

No. 892,926.

Specification of Letters Patent.

Patented July 7, 1908.

Application filed October 22, 1904. Serial No. 229,529.

To all whom it may concern:

Be it known that I, HENRY BARDSLEY, a citizen of the United States, residing at Providence, in the county of Providence and State of Rhode Island, have invented 5 certain new and useful Improvements in Loom Pattern Mechanism, of which the following is a specification.

My invention relates to loom pattern 10 mechanism of the class which has a pattern surface, preferably a pattern chain, for operating, through intermediate connections, the drop boxes, and a supplemental pattern surface, ordinarily called an auxiliary or multiplier pattern chain, for repeating 15 certain bars of the box pattern chain, in the ordinary and well known way; said box pattern chain and multiplier pattern chain having a ratchet and pawl operating mechanism in 20 the ordinary way.

The object of my invention is to improve upon the construction of the pattern mechanism of the class referred to, as ordinarily made, and more particularly to provide 25 reversing mechanism, for turning back the box pattern chain and the multiplier pattern chain, in case of picking out, or otherwise, in such a manner that they will not get out of time, and in case they should 30 get out of time they will automatically adjust themselves. And also to provide mechanism connected with the box pattern chain and the multiplier pattern chain, and also connected with any ordinary filling 35 stop motion of a loom, which mechanism acts to move the pawls, which operate the box pattern chain and the multiplier pattern chain, into an inoperative position, in case of the breaking or failure of filling.

40 And also to provide an improved pattern chain race or holder. All of said improvements may be combined with and applied to a box pattern chain, and a multiplier pattern chain, of any ordinary construction 45 and operation.

My invention consists in certain novel features of construction of my improvements as will be hereinafter fully described.

I have only shown in the drawings sufficient portions of a shuttle box pattern chain, and multiplier pattern chain and operating mechanism, with my improvements combined therewith, to enable those skilled in the art to which my invention

belongs to understand the construction 55 and operation thereof.

Referring to the drawings:—Figure 1 is a plan view of a box pattern chain and multiplier pattern chain mechanism, and my improvements combined therewith, looking 60 in the direction of arrow *a*, Fig. 2. Fig. 2 is a rear end view of the parts shown in Fig. 1, looking in the direction of arrow *b*, same figure. Fig. 3 is a section, taken at a point indicated by line 3, 3, Fig. 1, looking 65 in the direction of arrow *c*, same figure. Fig. 4 is a detached end view of the multiplier pattern chain cylinder and multiplier pattern chain, and a portion of the indicator lever, which is left out of Fig. 3, in order 70 to avoid confusion. Fig. 5 is a section, taken at a point indicated by line 5, 5, Fig. 1, looking in the direction of arrow *c*, same figure, showing some parts which are left out in Fig. 3, and, Fig. 6 is a section, taken 75 at a point indicated by line 6, 6, Fig. 1, looking in the direction of arrow *d*, same figure, with some parts left off.

The broken lines in Figs. 5 and 6 show the 80 opposite positions of some of the parts.

In the accompanying drawings, 1 is the end portion of a loom arch, to which is secured a stand 2, which forms a support for the several parts of the pattern mechanism. A shaft 4 suitably journaled has fast on one end 85 a hub 5' of a lever 5, which has an elongated slot 5" at its outer end to receive a stud 6, adjustable in said slot. On the stud 6 is pivotally mounted the hub 7' on the upright rod 7, the lower end of which is connected 90 with mechanism, not shown, which operates said rod 7 and, through lever 5, rocks the shaft 4, in the ordinary way.

The pattern chain shaft 8 is journaled in suitable bearings, and has the rotary box 95 pattern chain cylinder 9 secured thereon, carrying the flexible pattern chain 10 of ordinary construction, consisting of rolls 10' and tubes 10". Extending over the box pattern chain 10 are in this instance two box indicator 100 levers 11, and 12. On the pattern chain shaft 8 is fast at one end a hand wheel 8', and at the other end is loose a hand wheel 8", connected to the multiplier pattern chain cylinder 13. The multiplier pattern chain cylinder 13, 105 see Fig. 4, which carries the multiplier pattern chain 14, in this instance made up of what are termed risers and sinkers is loose

on the pattern chain shaft 8. 15 is the multiplier pattern chain indicator lever, which extends over and is engaged by the multiplier pattern chain 14. The multiplier pattern chain indicator lever 15 has a hub 15' which is loose on a shaft 16, journaled in suitable bearings. Extending out from the hub 15' is an arm 15'', having a projection 15''' thereon, and adjustable relative to its position on the shaft 16 by means of a bolt 18, extending through a slot 17''' in the arm 17, see Fig. 3. The arm 17 is made at its free end in the form of a shield. Also loose on the shaft 16 is the pattern indicator lever 19, which extends over the box pattern chain 10, and has a side extension 19' thereon connected by a bolt 20 with an adjustable arm 21, having a hub mounted on the shaft 16, and a projection 21' thereon. The other end 23 of the adjustable arm 21' is made in the form of a shield. Extending under the box pattern chain cylinder and the multiplier pattern chain cylinder are two stop levers 22, and 23, mounted on the shaft 4, and having arms 22' and 23' thereon connected to the springs 24 and 24', which springs are also connected to a transverse rod 25. Said springs 24 and 24' act to hold the curved ends of the stop levers 22, and 23, in engagements with the ratchet wheels 9^a and 13^a, connected respectively with the pattern chain cylinder 9, and the multiplier pattern chain cylinder 13, to hold said ratchet wheels, and the box pattern chain, and the multiplier pattern chain, in their proper positions.

26 is an arm or lever fast on the rock shaft 4, and having at its upper end a pin 26' on which are pivotally mounted a push pawl 27, and a pull pawl 28, which are adapted to engage respectively with the wheels 9^a and 13^a, and also adapted to be engaged by the shield portions on the arms 17 and 21, and be held out of operation by the same. The pawls 27 and 28 are provided at their outer ends with projections 27' and 28', see Fig. 1.

I will now describe my improvements in the reversing mechanism for turning back the box pattern chain 10, and the multiplier pattern chain 14.

50 A lever 29, having a handle 29', is pivoted at its lower end on the pattern chain shaft 8. The lever 29 has a pin 30 thereon, with its ends extending out from opposite sides of the lever 29. On the projecting ends of the pin 30 are pivoted two pawls 31 and 32, one of which, as 31, acts as a pull pawl, and the other, as 32, acts as a push pawl. Each of the pawls 31 and 32 has a weighted end 31' and 32', which act to hold the pawls, and also the lever 29 in their lowered position, shown by full lines in Figs. 5 and 6. One of the pawls, as 31, is adapted to engage the ratchet wheel 9^a, to turn the same backward, and the other of the pawls 65 as 32 is adapted to engage the ratchet

wheel 13^a, to turn the same in the opposite direction. The raising of the lever 29, to the position shown by broken lines in Figs. 5 and 6, causes the hubs on the pawls to engage the projecting ends 27' and 28', on the pawls 27 and 28, and raise them out of engagement with their respective ratchet wheels 9^a and 13^a. At the same time the movement of the lever 29, through the pull pawl 31 attached to said lever, reverses the box pattern chain barrel one pick, and the movement of the lever 29 in the opposite direction, by means of the push pawl 32 attached to said lever and engaging the wheel 13^a, reverses the multiplier pattern 80 chain one pick. The wheels 9^a, and 13^a are so constructed that they may be operated, either by a push or a pull pawl, and the pawls on the lever 29 are arranged just opposite to the pawls which move the 85 pattern chains forward.

I will now describe my improvements, combined with the box pattern chain and the multiplier pattern chain mechanisms, which act to move the pawl which operates 90 the box pattern chain, or the pawl which operates the multiplier pattern chain, (whichever one happens to be in action,) into an inoperative position, when the loom is stopped by reason of the breaking or failure of 95 filling, so that when the loom is again started the proper indications on the pattern chains will be under the indicator levers.

Loosely mounted on the shaft 16 is an 100 arm 33, having a side extension 33' thereon, which is adapted to engage the projections 17'' and 21'', on the arms 17 and 21, respectively. Connected with the arm 33 is a connector 34, which is connected with the 105 ordinary filling stop motion, not shown, which causes the connector 34 to move down the arm 33, when the loom is stopped by reason of the breaking or failure of the filling. The downward movement of the 110 arm 33 will cause the side extension 33' thereon to engage the projections 17'' and 21'', on the arms 17 and 21, to rock said arms, and cause the shield ends thereof to be raised, and to engage and raise the 115 pawls which operate the box pattern chain, and the multiplier pattern chain, so that said pawls will not operate the pattern chains.

I will now describe my improvements 120 which relate to the construction of the pattern chain race or holder.

Two separate side frames 35, have hubs 35' on their rear edge, through which passes the rod 25, and upon which they are secured by bolts 36, see Fig. 3. The front ends of the two side frames 35 are secured together and held in proper alignment by a tie rod 37. The front part of the chain race or holder, over which the chain passes, 130

consists of two bars 38, suitably grooved, which are connected at their lower ends by plates 39 with the side frames 35, and at their upper ends by plates 40, as shown in Fig. 3.

It will be understood that the multiplier pattern chain mechanism shown in the drawings and above described, is similar to the ordinary and well known form of ratchet multiplier pattern chain mechanism which causes the repetition of certain bars of the box pattern chain, but I have added to the ordinary multiplier pattern chain mechanism, a reversing mechanism, which I term a pull-back mechanism, by which both the multiplier pattern chain and the box pattern chain are turned back, pick by pick, without fear of changing their relation to each other.

With my improved mechanism the operator only needs to observe the number of picks which are removed, in case of picking out, and then move the pull-back lever back and forth the required number of picks. This operation will move back the chains. When my pull-back lever is not in use, the same is out of position and does not interfere with the ordinary operation of the pattern chains.

It will be understood that the details of construction of my improvements may be varied if desired.

Having thus described my invention, what I claim as new and desire to secure by Letters Patent is:—

1. In a loom pattern mechanism, of the class described, the combination with a box pattern chain, and a multiplier pattern chain, and pawl and ratchet mechanism for operating the same, of a reversing mechanism for turning back the box pattern chain, and the multiplier pattern chain, said reversing mechanism comprising a pivoted lever carrying two pawls, adapted to engage and turn the ratchet wheels of the pawl and ratchet mechanism of the box pattern chain and of the multiplier pattern chain, on the backward and forward movement of said lever.

2. In a loom pattern mechanism of the class described, the combination with a box pattern chain, a multiplier pattern chain, and pawl and ratchet mechanism for oper-

ating the same, of a reversing mechanism for turning back the box pattern chain and the multiplier pattern chain, said reversing mechanism comprising a pivoted lever carrying two pawls, one movement of said lever acting to reverse the box pattern chain, and the other movement of said lever acting to reverse the multiplier pattern chain.

3. In a loom pattern mechanism of the class described, the combination with a box pattern chain, and a multiplier pattern chain, and pawl and ratchet mechanism for operating the same, of a reversing mechanism for turning back, pick by pick, the box pattern chain and the multiplier pattern chain, said reversing mechanism comprising a pivoted lever carrying two pawls, a push pawl and a pull pawl, one pawl on one movement of said lever adapted to engage the ratchet wheel of the ratchet mechanism for operating the box pattern chain, to reverse it, and the other pawl on the other movement of said lever adapted to engage the ratchet wheel of the ratchet mechanism for operating the multiplier pattern chain, to reverse it.

4. In a loom pattern mechanism, the combination with the pattern chain, of a pattern chain race or holder, comprising two separate side frames secured together at their front part and held in proper alinement by a transverse rod, and said rod and secured at their rear part on a transverse rod, and said rod and two inclined bars having grooves therein for the pattern chain, and connected at their lower ends to the front part of the side frames, and at their upper ends to the upper rear part of the side frames.

5. In a loom pattern mechanism, the combination with the pattern chain, of a pattern chain race or holder, comprising two separate side frames secured together at their front part, and held in proper alinement, and secured at their rear part, and two inclined bars having grooves therein for the pattern chain, and connected at their lower ends to the front part of said side frames, and at their upper ends to the upper rear part of the side frames.

HENRY BARDSLEY.
